(57) **CLAIM**

The ornamental design for a video conferencing control device, as shown and described.

DESCRIPTION

FIG. 1 is a perspective view of the video conferencing control device.

FIG. 2 is a front elevational view of the video conferencing control device.

FIG. 3 is a rear elevational view thereof.

FIG. 4 is a top plan view thereof.

FIG. 5 is a bottom plan view thereof.

FIG. 6 is a left side elevational view thereof.

FIG. 7 is a right side elevational view thereof; and,

FIG. 8 includes environmental structure, namely a laptop computer, that forms no part of the claimed invention. The broken lines showing in FIG. 8 is environmental structure, namely a laptop computer, that forms no part of the claimed design.

1 Claim, 5 Drawing Sheets
